F. D. FORTNEY

BOOK

Filed Jan. 8, 1925

Frank D. Fortney,

J. V. Winters.

By

Attorney

UNITED STATES PATENT OFFICE.

FRANK D. FORTNEY, OF BROOKLYN, NEW YORK.

BOOK.

Application filed January 8, 1925. Serial No. 1,185.

To all whom it may concern:

Be it known that I, FRANK D. FORTNEY, a citizen of the United States, residing at Brooklyn, county of Kings, and State of New York, have invented certain new and useful Improvements in Books, of which the following is a full, clear, and exact specification.

This invention relates generally to books, 10 and particularly to bound volumes of that character wherein supplementary book sections are used therewith.

The primary object of the invention is to provide a book and its supplemental section 15 of such character that the said section may be removably secured within the book in such manner as to fill out the thickness of the same and thereby assist in preventing collapsing of the back of the permanently 20 bound volume, and which enables the said volume to present an appearance of completely filling out the space between the front and back covers.

A further and particular object of the invention is to provide a book of this character, the advantages of which are apparent, 25 featured by means of an improved and simplified nature for strengthening or reinforcing the back of the permanently bound 30 book to prevent creasing or collapsing of the same.

With these objects in view, together with others which will appear as the description proceeds, the invention resides in the novel 35 construction, combination and arrangement of parts, all as will be described more fully hereinafter, illustrated in the drawing, and particularly pointed out in the claim.

In the drawing:

40 Fig. 1 is a perspective view of a book constructed in accordance with the invention, a cover thereof being shown in raised position, and,

45 Fig. 2 is a transverse sectional view taken through the book with the covers in closed position.

The book or permanently bound volume 50 comprises the front and back cover members represented generally at 3, connected by the back member 4, the latter having secured as by glue, stitching or other preferred means, the back edges of the sheets or leaves of the book represented at 5. The back and cover members may be formed of 55 cloth or heavy paper as desired, and the

book may vary in thickness accordingly as occasion demands.

Associated with this permanently bound volume is a supplemental or removable book section, the leaves of which have secured thereto the cover members 7. The leaves of this supplemental volume may be secured to the back 8 thereof in a manner similar, as desired, to the method of securing the leaves of the main volume to its back.

In order that the supplemental volume may be associated within the covers of the permanently bound volume so as to lie properly within the same without protrusion or bulging, the back 4 of the main volume is of greater breadth than the body of leaves per se; the difference in breadth being substantially equal to the thickness of the supplemental book to be accommodated. One of the cover members 3 of the permanently 70 bound volume is provided upon its inner face with a pocket indicated generally at 9 to receive one of the covers 7 of the supplemental book. The cover 7 to be inserted within this pocket may have its lateral edges inclined as shown by dotted line in Fig. 1, so as to facilitate ready insertion of this cover member in said pocket.

That part of the back 4 of the permanently bound book which has no leaves secured thereto is reinforced or stayed by a 75 filler member 10 of substantial thickness, of a breadth equal to the space to be filled, and of a length equal to the height of the pages or leaves 5 of the volume. This filler member may be formed of one or more plies of relatively heavy cardboard or may be of wood or suitable metal. In the present instance, for the purposes of illustration, this 80 filler member is formed of heavy cardboard, and is glued or cemented securely to the back 4 of the volume. To rigidly anchor this 85 filler member in place, as well as to lend rigidity and strength to the entire book structure, the filler member 10 is glued or cemented inwardly from one end of a fabric member 11 of a length substantially equal to that of the leaves 5. The inner free end of this fabric is then passed around against and is glued to the back 4, with its extremity doubled back and glued within or between leaves 5 of the volume a substantial 90 distance from the adjacent edge of the filler member 10. The fabric member or anchor 95 is extended across the cover 3 and is rigidly 100 105 110

secured thereto, being doubled back upon itself a substantial distance and secured at its edges to provide the inwardly opening pocket 9 for the reception of the cover member 7 of the supplemental book. It will be understood, of course, that the leaves of the supplemental book are substantially equal in length and breadth to the length and breadth of the leaves 5 of the permanently bound volume. The supplemental volume is associated, as above described, with the permanently bound volume in such manner as to have its edges substantially coincide at all times with the edges 5 of the permanently bound volume of leaves. When the cover member 3 is opened, it carries with it the cover member 7 of the supplemental book, and the pages of the latter may be used for notations as desired. The leaves 6 of the supplemental volume are at all times available for use and may be turned as readily within the volume as removed therefrom, and the presence of the supplemental book within the covers of the main volume in no way interferes with proper manipulation or opening and closing of the main volume. The supplemental volume thus fits within and forms a component part of the main volume, and yet may be readily removed therefrom and replaced when desired. The particular structure employed in reinforcing the back preserves the construction of the latter as well as the appearance thereof, and danger of cracking, tearing or breaking of the same is obviated.

Having thus described my invention, I claim:

A book comprising a back member, a pair of covers flexibly connected to said back, a set of leaves secured to said back, the top of said set of leaves terminating short of the upper longitudinal edge of said back member, a filler member (10) located against the inner surface of said back member and extending a short distance outwardly thereof and filling the space adjacent said back member between the upper longitudinal edge of the latter and the top of said set of leaves, a fabric member for anchoring said filler member in place, said fabric member being secured to the front of said filler member and having its inner free end passed around against and secured to said back member with its extremity doubled back and secured within said set of leaves, the other end of said fabric member extending across the top cover, doubled upon itself a substantial distance and secured at its edges to define an inwardly opening pocket, and a supplemental book, comprising a cover member and having a body of leaves substantially equal in length and breadth to said set of leaves associated with said back member and substantially filling the space between the top of said set of leaves and said top cover, one end of said cover member being insertable within said pocket on said top cover for the purpose specified.

In testimony whereof I affix my signature.
FRANK D. FORTNEY.
